UNITED STATES PATENT OFFICE

WILLIAM H. DAY, OF CLINTON, CONNECTICUT, ASSIGNOR TO REMINGTON RAND INC., OF
BUFFALO, NEW YORK

INDEX OR FILE

Original application filed November 11, 1924, Serial No. 749,196. Divided and this application filed July 20, 1929. Serial No. 379,759.

This application is a division of application Serial No. 749,196, filed November 11, 1924.

This invention relates to index files or similar equipment, wherein a record carrying member is employed generally in the form of a shallow drawer or tray, capable of being stored away in a device in the form of a cabinet, and conveniently arranged for withdrawal therefrom in order to readily refer to the cards or sheets filed therein.

More particularly the invention relates to such an equipment using the type of index cards that lie substantially flatwise in the drawers in overlapped relation, whereby the margin of each is exposed to view, especially the type of index cards of the class shown in the Fisher Patent No. 1,048,056, granted December 24, 1912.

An index equipment such as that noted above, is shown in a co-pending application, Serial No. 669,525, of which this application in certain aspects is a continuation in part. This application relates, however, more specifically to an improved form of drawer or tray, adapted for use with such an equipment, and wherein novel filing and indexing means are provided.

In devices of this character, it is preferable to provide shallow sheet metal drawers or trays, having facilities for holding a comparatively large number of index cards, in order that the size of the cabinet may be held within reasonable and minimum dimensions.

The cabinets are adapted for general use in offices and elsewhere, and are arranged in such a manner that they may be placed in any handy location for ready reference, such as being placed upon the floor, table or desk, or even hung or placed beneath a table or desk.

Due to the possible use of this equipment in various locations, the drawers or trays must be of such construction that they will be readily adapted to the location wherever the cabinet is placed. The facilities for holding a comparatively large number of index cards, contained in each drawer, should be of such construction and arrangement that the index cards are held compactly and free from possible injury.

Being stored away within the cabinet, it is essential that the insignia of some kind be provided whereby the contents of each drawer may be noted at a glance, regardless of the location in which the cabinet is placed. Being shallow and usually stored in a cabinet wherein the front faces of the drawer are flush with or sunk beneath the front face of the cabinet, a suitable handle for withdrawing the same is necessary, especially one which will not interfere with the withdrawal of adjacent drawers.

One object, therefore, of this invention is to provide an index-receiving drawer or tray of shallow form, having facilities for holding a comparatively large number of cards compactly together, without danger of injury to the same due to interference of other cards in the same drawer, from the drawers above or below, or from foreign matter, such as dust or finger marks due to handling.

Another object of this invention is the provision for use in such a drawer of novel means for compactly holding a series of cards therein by the engagement thereof with the card edges while being capable of retaining a covering, preferably of a transparent nature, over the series of cards.

Still other objects of the invention comprise the provision of a drawer in which index cards may be readily filed, which is constructed wholly of sheet-metal, adapted for use in restricted vertical spaces, and which is inexpensive to manufacture.

To these and other ends, my invention consists in the novel features and combination of parts to be hereinafter described and claimed.

In the accompanying drawings:

Fig. 1 is a front elevation of an index cabinet of a type adapted to receive the drawers of this invention;

Fig. 2 is a plan view of a drawer or tray embodying the features of this invention;

Fig. 3 is an enlarged partial front view of the drawer or tray of Fig. 2, and a front view of the handle member applied thereto;

Fig. 4 is an enlarged side view of the parts shown in Fig. 3;

Fig. 5 is an enlarged partial plan view of

the front end of the drawer or tray and the handle member;

Fig. 6 is a section through the handle member, on line 6—6 of Fig. 4;

5 Fig. 7 is a section through the handle member on line 7—7 of Fig. 5;

Fig. 8 is a section on line 8—8 of Fig. 7;

Fig. 9 is an enlarged plan view of a portion of a drawer embodying the features of 10 this invention;

Fig. 10 is a section on line 10—10 of Fig. 9;

Fig. 11 is a section on line 11—11 of Fig. 9, and,

15 Fig. 12 is a view showing a modified arrangement of the filling facilities in a somewhat similar drawer.

The index equipment selected to illustrate the embodiment of my invention comprises a cabinet 10, suitably constructed to allow the 20 storing away of a plurality of drawers or trays 11, such as shown in Figs 2 and 12.

The drawer or tray 11, as illustrated, comprises a sheet metal structure having vertically extending flanged sides 12, which are integral with the bottom portion 14, being bent up therefrom, then inwardly over the drawer, and then returned back upon themselves outwardly and downwardly as at 12^a. Preferably, a strip of material bent in L-form in 25 cross-section, is inserted between the side portions 12 and 12^a to strengthen the same longitudinally. A drawer front plate 13 is provided for the drawer, which is vertically disposed and extends from one drawer side portion 12 to the other, and which braces the drawer transversely against distortion at the front edge thereof. This plate has one of its edges bent under the bottom portion 14, as at 13^a, where it is secured thereto by suitable 30 means, such as by spot welding, and the other edge bent backwardly over the drawer to form a flanged top edge 13^b for the drawer. The rear edge of the drawer bottom is bent angularly as at 14^a to brace the same transversely at this point. A plurality of suitable 35 transversely disposed index card supporting strips 15 are provided, suitably secured to the drawer bottom 14, which are adapted to slidably retain a plurality of index cards 16, which in this instance, are of the type shown in the above mentioned Fisher patent, and are arranged in overlapped relation with a margin 50 of each exposed to view. Flange members 17 and 17^a are provided, which extend substantially from one side of the drawer to the other, and are secured therein 40 in position to engage the edges of the cards 16.

The flange members 17 are of a novel form, 45 whereby provision is made for the protection of the cards 16, each being constructed of a strip of material, preferably sheet-metal, which is formed to provide a base portion 40, by which the member may be secured to the bottom 14 of the drawer by either spot-welding, as at 41, or other suitable means, a verti-

cal card edge abutment or web portion 42, a card edge protecting flange portion 43 and a transparent sheath edge-retaining socket 44. As illustrated in Figs. 10 and 11, the flange member 17 is bent up substantially at right-angles from the horizontally disposed base 40 to form the abutment 42, then bent horizontally to continue in the same direction as the base, but away therefrom to form the flange 43, and then returned back upon itself, forming a rounded edge 45 and the sheath socket 44. The card flange 43 and the sheath socket 44 are terminated short of both of the ends of the member 17 a sufficient distance to avoid the drawer side flanges 12, as shown respectively at 46 and 47, so that the cards 16 and the sheath 48 may be readily inserted in their proper positions. The cards 16 are engaged upon the strip 15 in this instance, by means of struck-out tongues, and have one of their side edges located below the flange 43 of one flange member 17 and abutting the web portion 42 of the same, the other edge being substantially in abutment with the web portion 42 of an adjacent member 17. One flange 43, therefore, acts as a retaining means to hold the cards downwardly and flatwise against the drawer bottom, while both webs 42 assist the strip 15 to hold the cards against twisting or other movement out of their proper position. The card-protecting sheath 48 is preferably transparent and is slipped into place by inserting one edge into the socket 44, and the other edge beneath the flange 43 of an adjacent member 17. By the use of a flange 90 member 17, as illustrated and above described, a plurality of series of index cards may be filed in a drawer with the side edges of adjacent series in close proximity without interference therebetween, whereby considerable space is saved in the drawer and the various series are held compactly together and free from interference by a partition between the drawers, or by the upper or lower drawer. By the use of the sheath member 48, the cards are protected from dust and finger marks or other injury, due to handling. The edges of the cards and accompanying sheaths immediately adjacent the front plate are received by the flange member 17^a which is a simple U-shaped flange having its bottom leg secured to the tray bottom 14 (Fig. 7).

The drawers 11 are as shallow as is practicable, in most cases being only slightly higher than the height of the series of superimposed cards therein. In this manner a large number of drawers may be stored into a cabinet of relatively small dimensions, thereby providing room for a considerable number of index cards. The card supports 125 15 obviously may extend longitudinally of the drawer, if such a position is desired, as shown in Fig. 12.

Each drawer is provided with a sheet-metal handle member 20, having a handle portion 130

21 and a base portion 21^a. The base portion 21^a is formed by bending downwardly an edge of the sheet-metal whereby the same may be secured to the drawer front face plate 13 by threading it through an elongated slot 18, suitably located in said front plate. The base portion 21^a may then be welded or otherwise secured against the inner surface 19 of the plate, preferably in a plurality of places, as shown at 22 in Fig. 8.

10 The handle or gripping portion 21 is formed as follows: The metal which extends through the plate horizontally, as at 23, is bent upwardly to form the shoulder 24 which 15 rests against the outer surface of the plate 13. The metal is then curved outwardly and downwardly as at 25, to a point slightly above the level of the drawer bottom 14, where it is turned as at 26 and curved upwardly and 20 back upon the portion 25 to form an upper or top portion 27. The metal forming the top portion 27, which terminates at 28, is limited in its upward extension so that it is slightly below the level of the upper edge of the 25 drawer front plate 13. At each side of the portion 25 and integral therewith is an ear 29 which is turned upwardly and supports and spaces the portion 27 from the portion 25. These ears or side portions 29 also act as 30 transverse strengthening flanges to insure that the curved shape of the handle portion 21 is retained.

35 The handle member 20 when formed as described above, produces and provides a useful and efficient device having a handle portion 21, which is easily grasped by the index finger and thumb of the user, and which is limited in vertical extension both upwardly and downwardly in respect to the levels of 40 the top and bottom of the drawer so that it is not liable to be interfered with by the drawer above or below when these are withdrawn. Preferably, the handles on adjacent drawers are located thereon in staggered relation, as shown in Fig. 1.

45 The bottom portion 25, top portion 27, and the side ears 29 of the handle portion 21 form a pocket 30 therein, which has a mouth opening 31 located closely adjacent the upper edge 50 of the front plate 13, formed between the termination 28 of the portion 27 and the front plate 13. An indicia-bearing slip 32 is located within the pocket 30, and may be observed by the user through a suitably provided window opening 33, formed in the top portion 27. Preferably, the slip 32 is covered with a transparent sheath 34 to protect the surface thereof, the sheath shown being folded about the slip 32.

55 The indicia upon the slip 32, due to the upwardly curved form of the portion 27, which is also given to the slip 32 when it is inserted in the pocket 30, are plainly visible to an observer either by looking directly toward the front of the drawer or directly down upon

the face of the drawer, which feature allows the cabinet to be located with respect to the user in a variety of positions. The handle member, therefore, aside from its value and usefulness as a handle for shallow drawers, 70 is also adapted for use as an indicia tab holder, and, therefore, forms an economically manufactured combined handle and tab holder. Due to the particular form of the handle member a strong and sturdy handle is provided, and because of the manner of attaching the same to the drawer there is little likelihood of its becoming loose or of bending under normal strains.

75 While I have shown and described a preferred embodiment of my invention, it will be understood that the same is not limited thereto in all of its details, but is capable of many modifications and variations which will fall within the spirit of the invention and the scope of the appended claims.

80 What is claimed is:

1. In an index or file, a drawer having means mounted therein for supporting index record members in overlapped relation, and means comprising a pair of members extending along the side edges of said index record members, one of said members having a flange overlapping a side edge of each of the record members, and the other member abutting the other edge.

85 90 95 100 105 110 115 120 125 130

2. In an index or file, a drawer having means mounted therein for supporting index record members in overlapped relation, means comprising a pair of members extending along the side edges of the record members, one of said members having a flange overlapping said record members at one edge, the other member abutting the opposite edge of the record members and presenting a groove beyond the card-abutting portion, said groove being in opposed relation with the overlapping portion of the first-mentioned member whereby a sheet of material may be held therebetween over said record members.

135 140 145 150 155 160 165 170 175 180

3. An index or file, a drawer having means mounted therein for supporting a plurality of parallel disposed series of index record members in overlapped relation, and means comprising a series of flanged members extending along between the side edges of adjacent series of said record members, each of said flanged members comprising a strip of material having a base portion, a portion bent upwardly from said base portion to form an abutment for the edges of the record members of two adjacent series, and a horizontally extending portion forming a flange to overlie one of said series of record-carrying members.

185 190 195 200 205 210 215 220 225 230

4. An index or file, a drawer having means mounted therein for supporting a plurality of parallel disposed series of index record members in overlapped relation, and means

comprising a series of flanged members extending along between the side edges of adjacent series of said record members, each of said flanged members comprising a strip of material having a base portion, a portion bent upwardly from said base portion to form an abutment for the edges of the record members of two adjacent series, a horizontally extending portion forming a flange to overlie one of said series of record-carrying members, and a portion turned backwardly over said horizontally extending flange to form a sheet-retaining groove.

5. In an index or file, a drawer having index card guides secured therein, a series of imbricated index cards mounted upon each of said guides, and a card edge retaining member, said member extending parallel with said card guides and presenting a flange extending over the exposed portion of the side margin of each of the cards in one series of said cards, and an abutment for the edges of the cards of the same and an adjacent series of cards.

25. 6. In an index or file, a drawer having index card guides secured therein, a series of index cards mounted upon each of said guides, and a card edge retaining member, said member extending parallel with said card guides 30 and presenting a flange extending over an edge of one of said series of cards, and an abutment for the edges of the cards of the same and an adjacent series of cards, and a flange portion for receiving an edge of a sheath member adapted to overlie said adjacent series of cards.

7. In an index or file, a drawer having series of index cards mounted therein, and a card edge retaining member, said member presenting a flange extending over the edges of one series of said cards, and an abutment for the edges of the cards of said series and another series, and a flange portion for receiving an edge of a sheath member.

45. 8. In an index or file, a flange member adapted to be secured upon an index card holder for engagement with the cards associated therewith, said member presenting a flange adapted to overlie an edge of the cards 50 and a shoulder adapted to abut an edge of the cards, and a flange adapted to receive an edge of a sheath member overlying the cards.

9. In an index or file, a flange member adapted to be secured upon an index card holder for engagement with the cards associated therewith, said member comprising a strip of material having a base portion, a shoulder portion, a flange portion, and a 55 sheath retaining flange portion, said base and first mentioned flange portions disposed substantially parallel to each other, and extending in opposite directions from said shoulder portion, said sheath-retaining portion extending from said first flange portion in the

same direction relatively to said shoulder, as said base portion.

10. In an index or file, a flange member adapted to be secured upon an index card holder for engagement with the cards associated therewith, said member comprising a strip of material having a horizontally disposed base portion, a vertically disposed shoulder portion, a horizontally disposed card-retaining flange and sheath socket portion.

11. In an index or file, a flange member adapted to be secured upon an index card holder for engagement with the cards associated therewith, said member comprising a strip of material having a longitudinally extending base portion, having means associated therewith extending upwardly therefrom, presenting on each side thereof an abutment and on one side a combined card-retaining flange and sheath socket.

12. In an index or file, a longitudinally elongated flange member adapted to be secured upon an index card holder, for engagement with the cards associated therewith, said member comprising a strip of material having a base portion, a substantially vertical shoulder portion, a card edge retaining portion and a sheath edge retaining portion, said base and card edge retaining portions extending from said shoulder portion in opposite directions, said sheath edge retaining portion extending from said card edge retaining portion back in the same direction as said base, each of said retaining portions terminating short of the end of said strip at one end thereof.

13. In an index or file, a flange member adapted to be secured upon an index card holder for engagement with the cards associated therewith, said member comprising a strip of material having a horizontally disposed base portion, a shoulder portion extending upwardly therefrom, a card edge retaining flange portion extending horizontally from said shoulder portion, and a sheath edge retaining portion extending back over said flange portion.

14. In an index or file, a longitudinally elongated flange member adapted to be secured upon an index card holder for engagement with the cards associated therewith, said member comprising a strip of material bent to form a horizontally disposed portion, a vertical portion, another horizontally disposed portion spaced above the plane of said first-mentioned horizontally disposed portion, but extending from said vertical portion in an opposite direction, and another horizontally disposed portion returned back over said second-mentioned horizontally disposed portion and spaced therefrom.

15. In an index or file, a drawer having index card guides secured therein, series of index cards mounted upon said guides, and

a card edge retaining member, said member extending parallel with said card guides and presenting a flange extending over an edge of one series of said cards, and an abutment 5 for the edges of the cards of the same and an adjacent series of cards, said abutment extending beyond said flange at one end thereof.

16. In an index or file, a flange member adapted to be secured upon an index card 10 holder for engagement with the cards associated therewith, said member presenting a flange adapted to overlie an edge of the cards and a shoulder adapted to abut an edge of the cards, said shoulder extending beyond 15 said flange at one end thereof.

17. In an index or file, a flange member adapted to be secured upon an index card holder for engagement with the cards associated therewith, said member comprising a 20 strip of material having a horizontally disposed base portion, a shoulder portion extending upwardly therefrom, a card edge retaining flange portion extending horizontally from said shoulder portion, and a sheath 25 edge retaining portion extending back over said flange portion, said shoulder extending beyond said flange portion and said sheath-retaining portion.

18. In an index or file, a flange member 30 adapted to be secured upon an index card holder for engagement with the cards associated therewith, said member comprising a strip of material having a horizontally disposed base portion, a shoulder portion extending upwardly therefrom, a card retaining edge flange portion extending horizontally from said shoulder portion, and a sheath 35 edge retaining portion extending back over said flange portion, said sheath-retaining portion stopping short of one end of said shoulder portion.

19. In an index or file, a flange member adapted to be secured upon an index card holder for engagement with the cards associated therewith, said member comprising a 45 strip of material having a horizontally disposed base portion, a shoulder portion extending upwardly therefrom, a card retaining edge flange portion extending horizontally from said shoulder portion, and a sheath 50 edge retaining portion extending back over said flange portion, said sheath-retaining portion and said flange portion being substantially coextensive and stopping short of 55 said shoulder portion at one end of said flange member.

WILLIAM H. DAY.
